[57] CLAIM

The ornamental design for a golf putter, as shown and described.

DESCRIPTION

FIG. 1 is a perspective view of a golf putter showing my new design;

FIG. 2 is a front view thereof;

FIG. 3 is a left side elevational view thereof;

FIG. 4 is a rear view thereof;

FIG. 5 is a right side elevational view thereof;

FIG. 6 is a top plan view thereof;

FIG. 7 is a bottom plan view thereof;

FIG. 8 is an enlarged fragmented perspective view of the putter head, shown for ease of illustration; and,

FIG. 9 is an enlarged fragmented perspective view of a second embodiment of the putter head, shown for ease of illustration.

The undisclosed sides of the second embodiment are identical to those disclosed in the first embodiment.
